UNITED STATES PATENT OFFICE

2,613,122

OPERATING MECHANISM FOR VENDING MACHINES

Homer G. Wells, Memphis, Tenn.

Application August 6, 1948, Serial No. 42,834

7 Claims. (Cl. 312—67)

1

This invention relates to operating mechanisms for vending machines, and is particularly adapted for use in connection with vending machines designed for the sale of merchandise such as packaged cigarettes, candy or the like.

Vending machines have been heretofore known which have incorporated a plurality of merchandise storage chutes in which each chute is independently operated and upon exhaustion of the merchandise contained in a single chute has required replenishment in order to continue the sale of that merchandise.

The principal object of the present invention is to provide a vending machine with a plurality of merchandise storage chutes in which the merchandise of the first chute is discharged through operation of the machine and the merchandise of the remaining chute or chutes is retained therein and prevented from discharge until after the exhaustion of the merchandise within the first chute.

A further object of the invention is to provide a vending machine with an operating mechanism which includes merchandise receiving and discharging means and merchandise supporting means whereby the merchandise of one column or chute is prevented from discharge until the exhaustion of the merchandise in another chute or column by the merchandise receiving and discharging means.

A further object of the invention is to provide in a vending machine, a merchandise discharging slide which is adapted to receive merchandise from a single column or chute thereof and which includes stop means adapted to position the merchandise receiving means beneath a chute or column containing merchandise.

A further object of the invention is to provide coin receiving means through which a suitable coin is introduced and positioned to serve as an abutment for the movement of a merchandise receiving and discharging slide and which mechanism includes means coupling the coin receiving means to the merchandise slide for return movement thereof.

A further object of the invention is to provide a resilient spring coupling between said members.

A further object of the invention is to provide such a spring coupling which is dimensioned to permit initial separation of the members at the beginning of return movement to free an interposed coin from any restraint against its gravity discharge.

And a further object of the invention is to

2

generally improve the design, efficiency and operation of operating mechanisms for vending machines.

The means by which the foregoing and other objects of the present invention are accomplished and the manner of their accomplishment will readily be understood from the following specification upon reference to the accompanying drawings, in which:

10 Fig. 1 is a side elevational view of the vending machine operating mechanism of the present invention, a suitable casing being shown thereon in dotted lines.

Fig. 2 is a top plan view of the operating mechanism of Fig. 1.

Fig. 3 is a sectional side elevation taken substantially on the center line of the operating mechanism.

Fig. 4 is a fragmentary sectional plan view on an enlarged scale, taken as on the line IV—IV of Figs. 1 and 3, and illustrating the position of the merchandise discharging slide after exhaustion of the merchandise from the first chute.

Fig. 5 is a fragmentary transverse sectional view on a further enlarged scale taken on the line V—V of Fig. 2.

Fig. 6 is a fragmentary sectional view taken on the line VI—VI of Fig. 5.

Fig. 7 is a fragmentary sectional side elevation on the scale of Fig. 4, taken on the line VII—VII of Fig. 2.

Fig. 8 is a fragmentary elevational view of the merchandise discharging slide and related parts of the merchandise chutes in the position of Fig. 4; and

Fig. 9 is an enlarged fragmentary sectional view of the lower portion of the mechanism showing the coin release.

Referring now to the drawings in which the various parts of the invention are indicated by numerals:

The present invention is designed as a unitary construction adapted for mounting in a suitable casing of such shape as is desired. As indicated in dotted lines on Figs. 1 and 3, the casing may be in the form of a camel or other animal shape, although it is not intended to limit the invention to the shape of the casing.

The operating mechanism is primarily mounted upon a slideway 11 which is preferably supported intermediate its length by vertically disposed supports 13, 15. The lower ends of the supports are preferably seated upon a suitable base 17.

55 Mounted upon and spaced above the slideway

11 are a plurality of merchandise containing chutes 19, the present illustration showing the use of two such chutes, although as will become apparent hereinafter, additional chutes may be added without departing herefrom. The chutes 19 are preferably attached and supported by straps 20 and are provided with a suitable cover formed of upright side walls 21, 22, front wall 23 and rear wall 24, and designed to house the vertically disposed chutes. The chutes are preferably separated as by a suitable partition 25 forming the rear wall of the forward chute illustrated. Slideway 11 is provided with inwardly facing longitudinally extending channel members 27 which are adapted to slidably receive and guide the slides of the operating mechanism. Slidably mounted on the slideway 11 is an operating slide 29 preferably having at its lower edge outwardly extending lugs 29A which are slidably engaged within the channel members 27.

The slideway 11 at its forward end is provided with an abutment 31 positioned to limit the forward movement of the operating slide 29 and at its rear end the slideway 11 is provided with a rear block 33. A merchandise receiving and discharging conveyor slide 35 is slidably mounted on the slideway 11 rearward of the operating slide 29 and is preferably provided with lugs similar to lugs 29A, and slidably engaging the channels 27 in a similar manner. The main body of the conveyor slide 35 is preferably of a thickness substantially equal to or slightly in excess of the thickness of a package of the merchandise to be vended by the machine, and has an imperforate, horizontal upper face 36. It will be noted that the lower end of the chutes 19 are spaced above the slideway 11 a distance to permit the sliding passage of the slide 35 therebeneath.

At its forward end the conveyor slide 35 is provided with a forwardly projecting tongue 37 and at its rear end is provided with a vertically disposed flange 39. Adjacent and forward of the flange 39 the slide 35 is provided with an aperture extending through the slide from top to bottom and of a size to receive a merchandise package from one of the chutes 19, as hereinafter described, said aperture forming with the underlying slideway a pocket for such deposited package.

The operating slide 29 is provided with a vertically disposed, transverse, coin-receiving slot 43 and is provided with a longitudinally extending aperture 45, the aperture 45 being positioned substantially centrally of the slide for the entry of the tongue 37 therein and being of a size to receive and permit the extension of the tongue therethrough. Supported from the abutment 31, as by support 47, is a coin chute 49, the upper end of which is adapted to receive coins deposited in the mechanism for the operation thereof, and the lower end of which is positioned to overlie the coin slot 43 when the operating slide 29 is in normal forward position against the abutment 31.

Mounted on and supported from the rear block 33, as by supports 51, is a suitable lever 53, shown in the present instance in the approximate form of a tail for the camel shaped casing, although it will be understood that the precise form of the lever forms no part of the invention. It will be seen that the lever 53 is pivoted to the supports 51 by a suitable pivot 55. Forwardly the lever is provided with a projection 57 to which is pivotally secured one end of a link 59, the opposite end of which is pivoted to an arm 61 intermediate the length of the arm. The arm 61 is

pivoted at its upper end to the side wall 22 and extends downwardly therefrom at a slight angle of inclination from the vertical. A second link 63 is pivoted at one end to the lower end of the arm 61 and at its opposite end is pivotally secured to the operating slide 29.

Adjacent its rear edge, the side wall 22 is preferably provided with a stop member 65 which is positioned and adapted to limit the rearward 10 arcuate movement of the arm 61 during operation of the device. Rear supports 51 are also preferably provided with a stop 67 positioned to be engaged by the forward portion of the lever 53 and to effect limitation of the arcuate movement of the lever 53.

As illustrated, the rear wall 24 of the chutes 19 is provided with an aperture 69 to permit the passage of the flange 39 therethrough and if additional chutes are to be added the rear wall 24 of each chute except the forward chute should be provided with a similar aperture. A return spring 71 is secured at one end preferably to the projection 57 of the lever 53 and at its opposite end to the side wall 22, the return spring 71 being 20 adapted to return the lever 53 to its normal position after operation, thereby reversing the movement of the links and arms, effecting return of the operating slide 29 to its initial normal position.

30 The conveyor slide 35 is coupled to the operating slide 29 by an elongated spring 73 to effect return movement of the conveyor slide 35 responsive to the return movement of the operating slide 29. Preferably the spring 73 is of a length 35 such that it is out of tension when the slides 29 and 35 are in the operating position shown in Fig. 3, so that a slight initial return movement of the operating slide 29 is required to bring the coupling spring 73 into tension and to thereby 40 begin the return movement of the conveyor slide 35, this delay permitting a slight separation of the slides at the beginning of the return movement.

Rearwardly of the rear chute wall 24 the slideway 11 is provided with a discharge opening 75 for the receipt of merchandise conveyed by the slide 35 and gravity discharge thereof, and preferably extending downwardly from the discharge opening 75 is a discharge chute 77, below which 50 may be positioned a suitable receptacle, not shown, for the receipt of objects discharged by gravity therefrom.

It will be seen that the main body of the conveyor slide 35 is provided with the imperforate upper face 36 which is adapted to underlie and to support merchandise contained in the chutes, preventing gravity urged movement of these objects.

In the operation of the device, merchandise, such as the cigarette packages 79, is stacked in the chutes 19 and the chutes being open at the bottom, the packages are ready for free discharge by gravity therefrom. In normal position, with both of the chutes loaded, the flange 39 of the slide 35 passes through the aperture 69 into contact with the rear edges of the merchandise in the rear chute 19, as is best illustrated in Fig. 7. In order to prevent possible damage to the packaged merchandise the flange 39 is preferably provided with a cushion 81 formed of sponge rubber or other suitable or similar material. When the slide 35 is positioned with the flange 39, or its cushion in contact with the rear edge of the package 79, the package receiving aperture 41 is positioned beneath the rear

chute and the lower package 79 is enabled to drop by gravity into the aperture 41 and to rest upon the slideway 11, the flange 39 being so positioned and the aperture 41 being so dimensioned that the lower package drops just before the cushion 81 moves into merchandise engaging position. The packages in the forward chute rest upon the imperforate upper face 36 of the conveyor slide 35 and are prevented thereby from gravity discharge from the chute.

In normal position the operating slide 29 is yielding held in contact with the abutment 31 by the action of return spring 11 and through the coupling spring 73 the slide 35 is held with the flange 39 in engagement with the packaged merchandise. When in this position the coin slot 43 is positioned below the lower end of the coin chute 49 to receive therefrom coins passing through the coin chute. It will be seen that in the absence of a coin in the coin slot 43 operation of the operating slide 29 by the lever and links will be ineffective to accomplish movement of the conveyor slide 35 as the tongue 37 will pass through the aperture 45 in the operating slide 29 and the stops 65 and 67 will prevent excess travel of the lever 53 and arm 61 so as to prevent undesired movement of the slide 35. When, however, a coin 82 is deposited in the coin chute 49 and passes therethrough into the coin slot 43, the coin is held in vertical position by the coin slot, the lower edge of the coin resting upon the slideway 11. This coin 82 is thus adapted to close off the aperture 45 and to provide an operating abutment adapted to engage the forward end of the tongue 37 to effect desired movement of the conveyor slide 35. When the coin has been thus positioned in the coin slot 43, outward movement of the lever 53 effects sliding of the operating slide 29, brings the coin into engagement with the forward end of the tongue 37 and moves the slide 35, and the package 79 contained in the aperture 41 is moved along the slideway over the discharge opening 75 and discharges by gravity into the discharge chute 77. It will be seen that the rear end of the slide 35 is then brought into engagement with the rear block 33 preventing accidental overtravel of the merchandise discharging slide. While the slide 35 is being moved to merchandise discharge, the remaining merchandise is retained in the chutes 19 by the imperforate face 36 of the slide 35.

When the slides have been moved sufficiently to accomplish discharge of merchandise, as just described, it is necessary that the coin 82 in the coin slot 43 should be removed therefrom so as to prevent repeated operation of the mechanism through the medium of a single coin. For this purpose the slideway 11 is provided with a coin discharge aperture 83 which preferably communicates with a passageway 85 leading downward through the forward support 13 into a suitable receptacle 87, preferably formed in the base 17. It will be seen that when the coin 82 is moved over the opening 83 it, if unrestrained, will fall by gravity therethrough into the coin passage 85 and will thereby interrupt the operating engagement of the forward end of the tongue 37.

It will be noted from Fig. 3 that the length of movement of the operating slide 29 is such as to position the coin slot 43 and the coin contained therein slightly to the rear of the center of the coin passage 85, although over the rear lip of the mouth of the coin aperture 83. This provision is made as the operating engagement of the

coin against the forward end of the tongue 37 under the operation of the lever 53 is such as to hold the coin between the end of the tongue and the edges of the coin slot 43, preventing gravity discharge of the coin therefrom. When, however, the lever is released, the return spring 71 acting on the lever 53 begins the reverse return movement of the operating slide 29, and in the manner already described, a slight separation of the parts occurs before the coupling spring 73 is brought into tension to begin the return movement of the slide 35, such separation of the parts being sufficient to completely release the coin and to insure its gravity discharge from the coin slot 43.

The return movement of the operating slide 29 moves the slide forward into engagement with the abutment 31 and accomplishes through the coupling spring 73 forward movement of the slide 35 until the flange 39 is brought into contact with the merchandise contained in the rear chute 19.

The operation of the mechanism is repeated with each coin insertion and the forward movement of the slide 35 arrested by the engagement of the flange 39 against the chute contained merchandise so long as the merchandise supply is not exhausted. When the supply of merchandise contained in the chute is exhausted the limitation effected by the engagement between such merchandise and the flange 39 is removed and the slide 35 on subsequent return movement moves forward until the flange 39 is in contact with the partition 25 (or if there is an intermediate chute, with the merchandise therein) and the merchandise receiving aperture 41 is brought beneath the chute to receive by gravity successive packages from the chute.

It is believed apparent that if additional merchandise chutes are desired they may readily be added with a slight change in the proportion of the parts and the operation thereof, in accordance with the foregoing description, may be readily accomplished.

Preferably the coin chute 39 is provided with a suitable coin detector 89, the details of which form no part of this invention, but which is provided to insure that only genuine coins may pass through the coin chute 49 into the coin slot 43. The coin passage 85 is preferably provided at its lower end with a window 91 through which coins inserted into the machine may be viewed. In order to retain the coin in position behind the window 91 a coin holder 93 is preferably secured in suitable manner, as by a screw, within the forward support 13, which is suitably slotted adjacent its lower end for that purpose. The coin holder 93 is preferably a flexible member having an intermediate portion 95 which is rearwardly offset from the upper portion of the holder, and a lower portion 96 attached to the intermediate portion and projecting forwardly therefrom to extend into the coin passage 85 adjacent and below window 91 and being adapted to receive coins thereon and to effect support thereof. Release of the coins from the coin holder 93 is effected through the medium of a rod 97, the lower end of which has a laterally projecting hook portion lying in the space between the intermediate portion 95 and the support 13, the upper end of the rod 97 being pivoted to an arm 98, the arm 98 being pivoted to the side wall 22. The forward end of the arm 98 is coupled to the operating slide 29 by a link 99.

It will be seen that upon operation of the slide

29 by the lever 53, the link 99 will cause upward movement of the arm 98, effecting upward movement of the rod 97, moving the laterally projecting hook portion thereof into engagement with the main portion of the coin holder 93, forcing that member rearwardly and moving the forwardly turned portion 96 out of the coin passage 85, thereby freeing the coin therein for gravity discharge into the coin receptacle 87.

I claim:

1. Operating mechanism for a vending machine, which comprises: a plurality of vertically disposed chutes adapted to receive merchandise packages and having open bottoms for gravity discharge of said merchandise packages therefrom, said chutes being positioned in alinement, a slideway longitudinally alined with said chute alinement spaced below said chutes and longitudinally extending oppositely beyond said chutes, a conveyor slide mounted on said slideway for sliding movement longitudinally of said slideway beneath said chutes, said conveyor slide having a merchandise supporting upper face and a merchandise receiving aperture, said conveyor slide having a vertical flange projecting upwardly from one end thereof, said aperture lying adjacent said flange and between said flange and said face, said slideway having a discharge opening therethrough positioned in the slideway extension adjacent said flange and aperture beyond said chutes, means for moving said slide longitudinally along said slideway in one direction to position said aperture over said discharge opening for gravity discharge of merchandise from said aperture into said opening, said face underlying said chutes during said movement to retain said merchandise therein, spring means urging opposite movement of said slide along said slideway effective on release of said moving means, said opposite movement of said slide moving said aperture to underlie one of said chutes, said chutes including vertical wall means positioned transverse said slideway, the said wall means of the chute most remote from said opening extending downwardly below the level of the upper end of said flange, the lower edge of the remaining said wall means being spaced above said slide for the passage of said flange therethrough, said opposite movement of said slide moving said flange into contact with merchandise contained in a chute to stop said opposite movement and position said aperture below said merchandise containing chute.

2. Operating mechanism for a vending machine, which comprises: a plurality of vertically disposed chutes adapted to receive merchandise packages and having open bottoms for gravity discharge of said merchandise packages therefrom, said chutes being positioned in alinement, a slideway longitudinally alined with said chute alinement spaced below said chutes and longitudinally extending oppositely beyond said chutes, a conveyor slide mounted on said slideway for sliding movement longitudinally of said slideway beneath said chutes, said conveyor slide having a merchandise supporting upper face and a merchandise receiving aperture, said conveyor slide having a vertical flange projecting upwardly from one end thereof, said aperture lying between said flange and said face, said slideway having a discharge opening therethrough positioned in the slideway extension adjacent said flange and aperture beyond said chutes, means for moving said slide longitudinally along said slideway to position said aperture over said discharge opening for gravity discharge of merchandise from said aper-

ture into said opening, said face underlying said chutes during said movement to retain said merchandise therein, spring means, urging opposite movement of said moving means, effective on release of said moving means, resilient means coupling said moving means to said slide to effect opposite movement of said slide along said slideway, responsive to opposite movement of the moving means, said oposite movement of said slide 10 moving said aperture to underlie one of said chutes, said chutes including vertical wall means positioned transverse said slideway, the said wall means of the chute most remote from said opening extending downwardly below the level of the upper end of said flange, the lower edge of the remaining said wall means being spaced above said slide for the passage of said flange therethrough, said opposite movement of said slide moving said flange into contact with merchandise 15 contained in a chute to stop said opposite movement and position said aperture below said merchandise containing chute, said resilient coupling means yieldingly holding said slide with said flange in movement limiting merchandise contact 20 and urging further opposite movement of said slide.

3. Operating mechanism for a vending machine, which comprises: a plurality of vertically disposed chutes adapted to receive merchandise packages and having open bottoms for gravity discharge of said merchandise packages therefrom, said chutes being positioned in alinement, a slideway longitudinally alined with said chute alinement spaced below said chutes and longitudinally extending oppositely beyond said chutes, a conveyor slide mounted on said slideway for sliding movement longitudinally of said slideway beneath said chutes, said conveyor slide having a merchandise supporting upper face and a merchandise receiving aperture, said conveyor slide having a vertical flange projecting upwardly from one end thereof, said aperture lying adjacent said flange and between said flange and said face, said slideway having a discharge opening therethrough positioned in the slideway extension adjacent said flange and aperture beyond said chutes, means for moving said slide longitudinally along said slideway in one direction to position said aperture over said discharge opening for gravity discharge of merchandise from said aperture into said opening, said face underlying said chutes during said movement to retain said merchandise therein, spring means urging opposite movement of said slide along said slideway effective on release of said moving means, said opposite movement of said slide moving said aperture to underlie one of said chutes, said chutes including vertical wall means positioned transverse said slideway, the said wall means of the chute most remote from said opening extending downwardly below the level of the upper end of said flange, the lower edge of the remaining said wall means being spaced above said slide for the passage of said flange therethrough, said opposite movement moving said flange toward abutment with said remote wall means, said abutment stopping said opposite movement of said slide.

4. In a vending machine, operating mechanism which includes a plurality of alined chutes adapted to receive merchandise and to deposit said merchandise by gravity, a conveyor slide longitudinally alined with said chutes and slideable along said alinement beneath said chutes, said slide having a merchandise receiving pocket and a merchandise supporting upper face adjacent

one side of said pocket, a vertical flange extending upward from said slide adjacent the other side of said pocket, said chutes including chute wall means open to permit the passage of said flange therethrough, merchandise discharge means adjacent said flange and aperture, means for moving said slide longitudinally in one direction toward said discharge means to merchandise discharge, and means for effecting return longitudinal movement of said slide in the opposite direction, said discharge movement moving said flange away from said chutes, said face underlying merchandise in said chutes and supporting said merchandise in said chutes during said movements of the slide, return movement of said slide moving said flange through said open wall means, said return movement moving said flange toward abutment with chute-contained merchandise, said abutment stopping return movement of said slide and positioning said pocket beneath the chute contained merchandise.

5. In a vending machine, operating mechanism which includes a plurality of aligned chutes enclosed by wall means, adapted to receive merchandise and to deposit said merchandise by gravity, a conveyor slide longitudinally aligned with said chutes and slideable along said alignment beneath said chutes, said slide having a merchandise receiving pocket and a merchandise supporting upper face adjacent one side of said pocket, a vertical flange extending upward from said slide adjacent the other side of said pocket, a portion of said chute wall means being open to permit the passage of said flange therethrough, means for moving said slide in one direction to merchandise discharge, discharge means spaced from said chutes in said one direction, and means for effecting return movement of said slide in the opposite direction, said discharge movement moving said flange away from said chutes, said face underlying said chutes and supporting the said merchandise in said chutes during said movements of the slide, return movement of said slide moving said pocket beneath chute-contained merchandise to receive deposit thereof, said flange being moved through said open chute wall means into contact with chute contained merchandise, said contact stopping return movement of said slide.

6. Operating mechanism for a vending machine which comprises a rear chute, and a front chute, said chutes being contiguous, vertically disposed, adapted to receive merchandise packages therein and having open bottoms for gravity discharge of said merchandise packages therefrom; a horizontally disposed slideway positioned below and spaced from said open bottoms a distance sufficient to permit the passage of a said package of merchandise therebetween, said slideway extending forwardly and rearwardly beyond said chutes, and having a discharge opening therethrough positioned rearwardly of said chutes; a conveyor slide mounted on said slideway for movement longitudinally thereof between said slideway and said chute bottoms, said slide having an aperture therethrough forming with said slideway a pocket adapted to receive a said package of merchandise from a chute containing merchandise when positioned therebelow, said slide adjacent and forward of said aperture having an imperforate face closely underlying the open chute bottoms and adapted to support chute contained merchandise when positioned therebeneath; means

5 for effecting rearward movement of said slide to move said aperture into register with said opening; means urging forward movement of said slide, and means limiting forward movement of said conveyor slide to position said pocket aperture for the reception of a merchandise package which comprise a vertical flange extending upward from said conveyor slide adjacent and rearward of said pocket aperture, and chute carried means disposed in the path of forward movement of said flange, the rear wall of said rear chute having an opening for the passage of said flange therethrough, forward movement of said conveyor slide moving said flange through said wall opening into movement stopping engagement with said chute carried means.

7. Operating mechanism for a vending machine which comprises a rear chute, and a front chute, said chutes being contiguous, vertically disposed, adapted to receive merchandise packages therein and having open bottoms for gravity discharge of said merchandise packages therefrom; a horizontally disposed slideway positioned below and spaced from said open bottoms a distance sufficient to permit the passage of a said package of merchandise therebetween, said slideway extending forwardly and rearwardly beyond said chutes, and having a discharge opening therethrough positioned rearwardly of said chutes; a conveyor slide mounted on said slideway for movement longitudinally thereof between said slideway and said chute bottoms, said slide having an aperture therethrough forming with said slideway a pocket adapted to receive a said package of merchandise from a chute containing merchandise when positioned therebelow, said slide adjacent and forward of said aperture having an imperforate face closely underlying the open chute bottoms and adapted to support chute contained merchandise when positioned therebeneath; means for effecting rearward movement of said slide to move said aperture into register with said opening; spring means urging forward movement of said slide, and means limiting forward movement of said conveyor slide to position said pocket aperture for the reception of a merchandise package which comprise a vertical flange extending upward from said conveyor slide adjacent and rearward of said pocket aperture, the rear wall of said rear chute having an opening for the passage of said flange therethrough, forward movement of said conveyor slide moving said flange through said wall opening into movement stopping engagement with merchandise in said chute, positioning said pocket aperture therebelow, merchandise in said front chute being supported by said face when said pocket aperture is below said rear chute, said pocket being moved beneath said front chute when said rear chute merchandise is exhausted.
